UNITED STATES PATENT OFFICE.

FRANK H. HARRIS, OF TOLEDO, OHIO.

WAGON RUNNING-GEAR.

SPECIFICATION forming part of Letters Patent No. 396,082, dated January 15, 1889.

Application filed April 10, 1888. Serial No. 270,193. (No model.)

To all whom it may concern:

Be it known that I, FRANK H. HARRIS, a citizen of the United States, residing at Toledo, in the county of Lucas and State of Ohio, 5 have invented certain new and useful Improvements in Wagon Running-Gears, of which the following is a specification, reference being had therein to the accompanying drawings.

10 This invention relates to certain new and useful improvements in wagon running-gears, and the invention is intended to apply to that class of toy wagons known to the trade as "boys' express-wagons."

15 The invention consists in the construction, arrangement, and combination of different parts, whereby economy of manufacture, combined with great strength and simplicity, is obtained, all as more fully hereinafter described.

In the drawings which accompany this specification, Figure 1 is a vertical central longitudinal section through a boy's express-wagon provided with my improved running-gear. Fig. 2 is a plan of the front gear. Fig. 3 is a vertical cross-section through the front gear through the center of the axle. Fig. 4 is similar cross-section through the hind axle. Fig. 5 is a detached perspective view of the 25 rear axle-bolsters. Fig. 6 is a cross-section through the fastening by means of which the front and rear axle bolsters are secured to the axles, and Fig. 7 is a detached perspective view of the draft-iron.

30 A is the body of the wagon, which is of any suitable and known construction.

B are the front wheels, and B' the hind wheels.

C is the front axle, and C' the rear axle, 40 upon which the wheels are journaled in the usual manner.

D is an arched metallic axle-cap, supported near its outer ends on the top of the axle, and secured thereto by means of the clamping-boxes E, one of which is shown in cross-section in Fig. 6, and which consists of the upper half, a, formed integrally with the axle-cap, and the lower half, b, formed in a separate piece and secured to the half a by means of 45 the single rivet or bolt, c, at one end and by means of the hook d at the other end, said hook d engaging slidingly with the lip e,

formed in the corresponding part of the upper half of the box. This lip e is formed wedge-shaped, as shown, so as to firmly wedge 55 into the hook d when the parts are laterally engaged with each other.

One or more studs, f, may be cast on the under side of the cap D, to engage into corresponding holes or recesses formed in the axle 60 to receive them; or ears g may be formed in pairs on this axle-cap to embrace the axle between them. By this means the axle-cap D is firmly secured to the axle and acts as a truss. The central portion of the axle-cap is 65 raised to form a circular bearing or fifth-wheel, F, upon which the bolster turns, and which forms below the recess G, of such form and dimensions as to confine the nut H, by means of which the king-bolt I is secured and 70 thereby prevents said nut from being turned off.

J is an arched metallic bolster, integrally provided at its outer ends with suitable flanges, h, to secure it to the under side of the 75 wagon-body and at its central part with the circular bearing i and the king-bolt I. This king-bolt is screw-threaded and projects through a suitable aperture in the cap D, and receives at its lower end the nut H, which, as 80 before described, is prevented from turning. Thus to engage the parts of the forward running-gear together, the king-bolt I has to be screwed into the nut before the bolster J is secured to the body of the wagon. By this 85 means the frequent accidents caused by the loss of the king-bolt are made impossible with my construction; and, further, the number of rivets or bolts to secure the parts together is reduced to a minimum without impairing the 90 strength of the structure.

K are forwardly-projecting hounds, preferably integrally formed with the cap D and terminating at their forward ends in the inwardly-projecting hooks j.

L is the pole, and to the rear end of this pole are secured the draft-irons M, the rear ends of which are provided with suitable holes, k, which engage with the hooks j of the hounds, and the forward end of these draft-irons M are provided with the bolt-hole m, to enable it to be secured to the end of the pole, and with the studs l, which are driven into the pole, thereby securing the parts more firmly 95 100

together and making the pole non-detachable from the running-gear, so that it cannot be lost, as otherwise might occur. In shipping, the pole may be conveniently folded back under the wagon, as shown in dotted lines in Fig. 1.

5 N are metallic supports for the rear end of the body. They are provided at their upper end with suitable flanges, *n*, for securing them, 10 by means of bolts or otherwise, to the under side of the wagon-body, and at the lower ends they are provided with the laterally-projecting caps *o*, which fit on top of the axle, and are secured thereto by means of clamping- 15 boxes *E*, which are constructed the same as the clamping-box for securing the axle-cap *D* to the front axle. The studs *p* are provided on this cap in like manner and for corresponding purpose as described for the front 20 cap *E*.

What I claim as my invention is—

1. The combination, in a wagon running-gear, of the front axle, the arched cap secured to said axle, the recess formed on the under 25 side of said cap, the screw-threaded king-bolt engaging into said cap, and the nut for securing said king-bolt engaging into the recess of said cap to keep it from turning off, and the arched bolster supported by said cap, substantially 30 as described.

2. The combination, with the front and rear axles of an express-wagon, of the clamping-

boxes *E*, consisting of the upper part, *a*, integrally formed with the axle-cap or support, and provided with the lip *e* and the part *b*, 35 secured thereto and provided with the hook *d*, substantially as described.

3. The combination of the front axle, *C*, the axle-cap *D*, secured thereto, the forwardly-projecting hounds *K*, integrally formed therewith and provided with the inwardly-projecting hooks *j*, the pole *L*, and the draft-irons *M*, provided with the eyes *k* at their rear ends and secured to the pole at their forward ends, 40 substantially as described. 45

4. In a wagon running-gear, the combination, with the front axle, *C*, of the arched cap *D*, the clamping-boxes *E*, securing it to the front axle, the recess *G*, formed in the under side of the cap, the circular bearing *F*, formed 50 on top of the cap *D*, the arched bolster *J*, secured to the wagon-body and provided with the circular bearing-plate *i*, the screw-threaded king-bolt *I*, and the king-bolt nut *H*, seated in the recess of the cap *D*, substantially as described. 55

In testimony whereof I affix my signature, in presence of two witnesses, this 13th day of March, 1888.

FRANK H. HARRIS.

Witnesses:

P. M. HULBERT,
H. S. SPRAGUE.
